UNITED STATES PATENT OFFICE.

EDWARD L. NORTON, OF NEW YORK, N. Y., ASSIGNOR TO WESTERN ELECTRIC COMPANY, INCORPORATED, OF NEW YORK, N. Y., A CORPORATION OF NEW YORK.

ELECTRICAL NETWORK.

Application filed March 31, 1926. Serial No. 98,649.

This invention relates to electrical networks and particularly to transmission equalizing networks of the type known as constant resistance networks and has for 5 an object to improve such networks.

U. S. Patent No. 1,603,305, issued October 19, 1926, to O. J. Zobel, describes various 10 forms of constant resistance equalizing networks and gives a discussion of the general properties of this type and the method of 15 its application to the equalization of attenuation in transmission systems.

A particular object of this invention is 20 to reduce the number of impedance elements required for the construction of a constant 25 resistance network having a characteristic which provides a specified attenuation correction.

A further object of the invention is to 30 provide a constant resistance network which may be connected between two terminating 35 circuits having different impedances.

In general this invention consists of a 40 constant resistance transmission correcting 45 network comprising a bridged T arrangement of elements in which the two series arms of the bridged T are not alike. However, the particular characteristics of the 50 networks of this invention can be best understood by reference to the following detailed description in connection with the drawing in which: Figs. 1, 3, 5 and 6 show 55 generalized impedance diagrams of the networks of this invention, Figs. 2, 4 and 7 equivalent networks of the Zobel type and 60 Figs. 8 and 9 specific examples of the networks of this invention.

This invention in its general form may 65 be represented by the two generalized impedance structures shown in Figs. 1 and 3. The networks of Figs. 5 and 6 are identical with Figs. 1 and 3, respectively except that 70 different points are used for terminals.

The form of the invention shown in Fig. 75 1 comprises a network connected between the two sets of terminals 1, 2 and 3, 4. The resistance connected to the terminals 3, 4 represents a load circuit having a constant 80 resistance impedance, R_1 . The network 85 consists of two impedances $cZ_1 + aZ_2$ and Z_1 connected in series between the terminals 1 and 3, a resistance R bridge across these im-

pedances between terminals 1 and 3, a shunt impedance bZ_1 having one terminal connected to the junction of $cZ_1 + aZ_2$ and Z_1 55 and a shunt impedance Z_2 connected between the terminals 3 and 4.

The form of the invention shown in Fig. 3 is somewhat similar consisting of a network connected between the terminals 7, 8 60 and 9, 10, the resistance connected to the terminals 9, 10 representing a load circuit having a constant resistance impedance R_2 . This network consists of a series arm $aZ_2 + cZ_1$ connected in series with a bridged T 65 type network having unequal series arms (as in the form shown in Fig. 1), Z_2 and Z_1 bridged by an impedance bZ_1 and a shunt arm of resistance R connected to the junction of Z_2 and Z_1 .

By elementary analysis based on Kirchhoff's laws it can be shown that these networks have a constant resistance impedance R at their terminals 1, 2 and 7, 8, respectively when:

$$R^2 = Z_1 Z_2 a (1 + b)$$

$$c = a(1 + b) - \frac{b}{1 + b}$$

and, (for Fig. 1)

$$R_1 = \left(\frac{1 + b}{1 - b} \right) R$$

or, (for Fig. 2)

$$R_2 = \left(\frac{1 - b}{1 + b} \right) R$$

In designing networks of this type it is 90 most convenient to refer to the equivalent network of the series-shunt type, formulae for the design of which together with examples are given in the patent to Zobel referred to above. Reference is also made to Chapter XVIII of Transmission Circuits 95 for Telephone Communication by K. S. Johnson, Van Nostrand and Company.

Fig. 2 shows a full series terminated network of the type described by Zobel which has a transmission characteristic equivalent 100 to that of the network of Fig. 1. Fig. 4 shows a full shunt terminated network having a transmission characteristic equivalent to the network of Fig. 3. The networks of

Figs. 2 and 4 are of the types shown in Figs. 9 and 10 respectively of the Zobel patent and Figs. 1^A and 1^B respectively of the chapter of the K. S. Johnson book referred to above, in which Z_{11} is composed of two impedances A and B in series, and Z_{21} of two impedances C and D in parallel. As indicated in the drawings:

$$10 \quad \begin{aligned} A &= a(1+b)^2 Z_1 \\ B &= a(1+b) Z_2 \\ C &= \frac{Z_2}{1+b} \end{aligned}$$

15 and

$$D = Z_1.$$

The transmission loss in transmission units, caused by these structures is,

$$20 \quad TU = 20 \log_{10} \left(1 + \frac{Z_{11}}{R} \right)$$

25 The transmission loss caused by the networks of Figs. 1 and 2 is equal to this plus a constant loss equal to the reflection loss between the input resistance and the terminating resistance thus:

For Fig. 1

$$30 \quad TU = 20 \log_{10} \left(1 + \frac{Z_{11}}{R} \right) + 20 \log_{10} \left[\frac{R + R_1}{2\sqrt{RR_1}} \right]$$

and for Fig. 2

$$35 \quad TU = 20 \log_{10} \left(1 + \frac{Z_1}{R} \right) + 20 \log_{10} \left[\frac{R + R_2}{2\sqrt{RR_2}} \right]$$

in which by definition:

$$40 \quad \begin{aligned} Z_{11} &= A + B = a(1+b)^2 Z_1 + a(1+b) Z_2 \\ Z_{11} &= a(1+b) [(1+b)Z_1 + Z_2]. \end{aligned}$$

45 The networks of this invention may also be used for operating between an input resistance and a load resistance which are equal as shown in Figs. 5 and 6.

50 The network of Fig. 5 is identical with that of Fig. 1 except that a load circuit of constant impedance R is connected to the terminals 5, 6 whereas in Fig. 1 a load circuit of constant impedance R_1 is connected to terminals 3, 4. Similarly the network of Fig. 6 is identical with that of Fig. 3 except that a load of constant impedance R is connected to the terminals 11, 12 in place of a load circuit of constant impedance R_2 connected to the terminals 9, 10.

55 The networks of these two figures have transmission characteristics equal to that of the equivalent bridge network of the type shown in Fig. 5 of the Zobel patent and Fig. 1^E of the chapter of the K. S. Johnson book referred to above. The equivalent network is composed of series arms Z_{11} comprising two impedances C and D and a resistance R_1 in parallel and shunt arms Z_{21} comprising

60 ing two impedances A and B and a resistance R connected in series, in which:

$$\begin{aligned} A &= 2a(1+b)Z_1 \\ B &= 2aZ_2 \\ C &= \frac{Z_2}{2} \\ D &= (1+b)\frac{Z_1}{2} \end{aligned}$$

65 and for the equivalent of Fig. 5,

$$\begin{aligned} R_3 &= \frac{R^2}{R_1} \\ R_4 &= R_1 \end{aligned}$$

70 or, for the equivalent of Fig. 6,

$$\begin{aligned} R_3 &= R_2 \\ R_4 &= \frac{R^2}{R_2}. \end{aligned}$$

75 The transmission loss, in transmission units, caused by this structure is:

$$80 \quad TU = 20 \log_{10} \frac{\frac{Z_{21}}{R} + 1}{\frac{Z_{21}}{R} - 1}$$

85 in which

$$Z_{21} = R_3 + A + B$$

90 which is, for Fig. 5,

$$\begin{aligned} Z_{21} &= \frac{R^2}{R_1} + 2a(1+b)Z_1 + 2aZ_2 \\ Z_{21} &= \frac{R^2}{R_1} + 2a[(1+b)Z_1 + Z_2] \end{aligned}$$

95 or for Fig. 6.

$$100 \quad Z_{21} = R_2 + 2a[(1+b)Z_1 + Z_2].$$

105 The networks of Figs. 5 and 6 can be seen to require considerably fewer elements than is required for the network of Fig. 7. Thus by the use of this invention it is possible to obtain at a considerable saving in elements the same transmission characteristic as is obtained with the bridge type network of Fig. 7.

110 Figs. 8 and 9 show specific examples of the circuits of type of Figs. 1, 5 and 2, 6 respectively in which Z_1 is a condenser of capacity C and Z_2 a coil of inductance L. These circuits, of course, only show particular embodiments of the invention and any combination of elements which will give the transmission characteristic desired may be used for the generalized impedances Z_1 and Z_2 .

115 120 What is claimed is:

125 A wave transmission network having a pair of input terminals and a pair of output terminals adapted to be connected to a load circuit having a substantially constant resistance impedance over a range of frequencies, said network comprising an impedance element connected directly between 120 125

an input terminal and an output terminal, a pair of unequal impedance elements having a common terminal and having their other terminals connected respectively to the 5 terminals of said first impedance element, and a fourth impedance element having one terminal connected to said common terminal and having connections from its other terminal to the remaining input and output terminals, the impedances of the elements of

said network being so proportioned with respect to one another and to the impedance of the load circuit that the input impedance of said network is a constant resistance over said range of frequencies.

15

In witness whereof, I hereunto subscribe my name this 29th day of March A. D., 1926.

EDWARD L. NORTON.
